FOLDING FLIGHT TRAINING HOOD

Bernard B. Helfand, deceased, late of Tiburon, Calif., by
Phyllis Jones Neidig Helfand, executrix, 240 Loma Ave.,
Tiburon, Calif. 94920

Filed May 20, 1974, Ser. No. 471,318

Term of patent 14 years

Int. Cl. D2—03

U.S. Cl. D2—234

Fig. 5

Fig. 6

Fig. 7

FIG. 1 is a perspective view of a folding flight training hood illustrating the new design;
 FIG. 2 is a right side view thereof;

FIG. 3 is a front view thereof;

FIG. 4 is a rear view thereof;

FIG. 5 is a top view thereof;

FIG. 6 is a bottom view thereof; and

FIG. 7 is a view of the flight training hood folded.
 I claim:

The ornamental design for a folding flight training hood, substantially as shown.
